UNITED STATES PATENT OFFICE.

CHARLES P. EISENHAUER, OF DAYTON, OHIO.

DESIGN FOR A PUMP CASING.

Application filed November 6, 1922. Serial No. 4,234. Term of patent 3½ years.

To all whom it may concern:

Be it known that I, CHARLES P. EISENHAUER, a citizen of the United States, residing at Dayton, in the county of Montgomery, State of Ohio, have invented a new, original, and ornamental Design for Pump Casing, of which the following is a specification, reference being had to the accompanying drawing, forming a part thereof.

In the drawing, Fig. 1 is a front per-

spective view of the article, showing my new design. Fig. 2 is a rear perspective view thereof.

I claim:

The ornamental design for a pump casing as shown.

In testimony whereof I have hereunto set my hand this 13th day of January, A. D. 1922.

CHARLES P. EISENHAUER.
